AIRPLANE

Elma O. La Fave, 1745½ N. Garfield Place,
Hollywood, Calif.

Filed Jan. 20, 1964, Ser. No. 78,265

Term of patent 14 years

(Cl. D71—1)

FIG. 1 is a side elevational view of an airplane, showing my new design.

FIG. 2 is a front elevational view thereof.

FIG. 3 is a top plan view.

FIG. 4 is a bottom plan view of the nose of the airplane.

I claim:

The ornamental design for an airplane, substantially as shown.
